UNITED STATES PATENT OFFICE.

WILLIAM H. CAIN, OF COLUMBUS, OHIO, ASSIGNOR OF ONE-HALF TO
CHARLES O. GASS, OF COLUMBUS, OHIO.

MEANS FOR REGULATING AND CONTROLLING GAS-SUPPLY.

No. 831,262.

Specification of Letters Patent.

Patented Sept. 18, 1906.

Application filed September 29, 1905. Serial No. 280,662.

To all whom it may concern:

Be it known that I, WILLIAM H. CAIN, a citizen of the United States, residing at Columbus, in the county of Franklin and State of Ohio, have invented certain new and useful Improvements in Means for Regulating and Controlling a Gas-Supply; and I do hereby declare the following to be a full, clear, and exact description of the invention, such as will enable others skilled in the art to which it appertains to make and use the same.

The object of this invention is to provide an improved means for regulating and controlling the supply of gas to cities and towns.

In supplying gas to cities and towns it is important that the supply be kept as nearly uniform and constant as possible and that repairs may be made without cutting off the supply.

To these ends the invention consists in the combination and arrangement of parts hereinafter described and claimed.

In the accompanying drawings, Figure 1 is a general or diagrammatic view of the apparatus, and Fig. 2 is a detail sectional view of a strainer used in the apparatus.

In the views, 3 designates the field or primary supply-line, and 4 the city or controlled line. Between the field-line and the controlled line are laid and connected two main controlling-lines 5 and 5^a and two auxiliary or by-pass lines 6 and 6^a. In the main controlling-lines I make loops 7 and 7^a. At suitable intervals in the main controlling-lines is a series of diaphragm-equalizing or pressure-reducing devices 8, 9, and 10 and 8^a, 9^a, and 10^a, respectively, of ordinary construction, each companioned at each side by ordinary gate-valves 11. The equalizing devices 8, 9, and 10 and 8^a, 9^a, and 10^a can be made in removable sections of pipe, so that they can be removed for repairing the equalizing device, the gates on opposite sides

45 permitting the pipes to be closed for this purpose. The auxiliary or by-pass lines 6 and 6^a tap the field-line beyond the junction with the field-line of the two main controlling-lines 5 and 5^a. The auxiliary lines are also 50 connected with the main controlling-lines at points between the series of pressure-reducing devices by short pipes or by-passes 12, inclined to the direction of motion of the gas through both lines. By the use of inclined

pipes and Y-couplings, as shown, the flow of 55 the gas is less impeded.

13 designates a gate for shutting off or regulating the quantity of flow from the field.

14 designates a similar gate for shutting off the gas in the city-line.

15 designates a gate for shutting off the gas from the field to the main controlling-lines 5 and 5^a for the purpose of directing the supply into the auxiliary or by-pass lines.

16 represents gates in the auxiliary line 65 between the short connecting-pipes 10.

17 represents ordinary gages in the auxiliary pipe 6 and 6^a to indicate the pressure from the field-line, and 18 represents similar gages in the main controlling-line indicating 70 the pressure at which the gas is discharged into the city-line.

19 represents escape-pipes from the main controlling-line provided with a regulated safety-valve 20 for relieving undue pressure 75 in the main controlling-lines 5 and 5^a.

21 designates pipes with provided cocks 21^a for discharging liquids that might accumulate in the lines 5 and 5^a.

22 represents tanks containing water and 80 oil into which the open ends of the by-pass lines 6 and 6^a are submerged, said tanks being provided with suitable vents to carry off excess pressure, if necessary, in said auxiliary lines.

23 designates a filter interposed between the junction of the pipes 5 and 5^a and the valve 15, consisting of two heads with a screen 23^a, bolted tightly between them. The filter is provided with a cocked vent 23^b.

In practice the pipes 5 will preferably be laid on the floor or ground and the pipes 6 and 6^a directly above and parallel to them. The loops 7 and 7^a will extend horizontally from the lines 5 and 5^a. The drawings, therefore, 95 it will be understood, are merely diagrammatic.

The series of equalizers or pressure-reducing devices 8, 9, and 10 and 8^a, 9^a, and 10^a are graduated from high to low in power.

The function of the loops 7 and 7^a is to provide suitable room for the settling of the flow between the first two pairs of reducing devices without the occupation of extensive floor-space and the erection of a more costly 105 building.

The operation of the system is as follows: If any of the equalizing or pressure-reduc-

ing devices in the main regulating-line needs repairs or attention it may be isolated by closing the companion gates and the flow of gas that flowed through it or them directed 5 into one or both of the by-pass lines. For example, if the pressure-reducing device 9 should become deranged it can be isolated for repairs by closing its companion gates and opening the two right-hand gates 16 and 10 then directing the gas through the by-pass line 6 and the middle inclined pipe 12 at the left of the device 9.

Should the screen 23^a become clogged by the accumulation of foreign things, it may be 15 cleansed by closing the gate 15, opening the right-hand gate 16 in one or the other of the by-passes 6 6^a and the cock in 23^b, thus establishing a back flow through the screen and blowing out the clogging material.

20 The pressure of the inflowing and outflowing gas can be noted at all times by watching the gages 17 and 18 and the reducing devices regulated accordingly.

Further, by this apparatus one of the pressure-regulators can be left cut out and normally inactive to be put into use while a defective one is being repaired, thus insuring the maintaining of a uniform pressure in the controlled line.

30 What I claim, and desire to secure by Letters Patent, is—

1. In means for regulating and controlling a supply of gas, the combination with a field-line and a controlled line, of a main controlling-line between the field and controlled 35 lines provided with a plurality of pressure-reducing devices companioned by cut-off gates at each side thereof, and a by-pass line provided at intervals with gates, and pipe connections 12 alternating with said last-named gates at three or more points of the by-pass line with the main controlling-line and between adjacent gates of the main controlling-line.

2. In means for regulating and controlling 45 a supply of gas, the combination with a field-line and a controlled line, of a main controlling-line between the field and controlled lines provided with a plurality of pressure-reducing devices companioned by cut-off gates 50 at each side thereof and a by-pass line provided with a loop and at intervals with gates, and pipe connections 12 alternating with said last-named gates at three or more points of the by-pass line with the main controlling-line and between adjacent gates of the main 55 controlling-line.

3. In means for regulating and controlling a supply of gas, the combination with a field-

line and a controlled line, of a main controlling-line between the field and controlled lines provided with a plurality of pressure-reducing devices companioned by cut-off gates at each side thereof, and a by-pass line provided at intervals with gates, and inclined pipe connections 12 alternating with said last-named gates at three or more points of the by-pass line with the main controlling-line between adjacent gates of the main controlling-line.

4. In means for regulating and controlling a supply of gas, the combination with a field-line and a controlled line, of a plurality of main controlling-lines between the field and controlled lines each provided with pressure-reducing devices companioned by cut-off 7 gates at each side thereof, and by-pass lines each provided at intervals with gates, and pipe connections 12 alternating with said last-named gates at three or more points of the by-pass lines with the main controlling- 8 lines and between adjacent gates of said controlling-lines.

5. In means for regulating and controlling a supply of gas, the combination with a field-line and a controlled line, of a plurality of main controlling-lines between the field and controlled lines each provided with pressure-reducing devices companioned by cut-off gates at each side thereof, and by-pass lines each provided at intervals with gates, and inclined connections 12 alternating with said last-named gates at three or more points of the by-pass lines with the main controlling- 9 lines and between adjacent gates of said controlling-lines.

6. In means for regulating and controlling a supply of gas, the combination with a field-line and a controlled line, of main controlling-sections provided with pressure-reducing devices companioned by cut-off gates at each 10 side thereof, by-pass sections connected with the field-line beyond the connection of the main controlling-section thereof and at intervals with the main controlling-sections between the pressure-reducing devices, gates in 11 said by-pass sections, a gate and a filter between the junction of the main controlling and the junction of the by-pass sections with the field-line and a gate between the filter and said junction, substantially as described. 12

In testimony whereof I affix my signature in presence of two witnesses.

WILLIAM H. CAIN.

Witnesses:

OLIN J. ROSS,
BENJ. FINCKEL.

It is hereby certified that the name of the assignee in Letters Patent No. 831,262, granted September 18, 1906, upon the application of Willlam H. Cain, of Columbus, Ohio, for an improvement in "Means for Regulating and Controlling Gas-Supply," was erroneously written and printed "Charles O. Gass," whereas the said name should have been written and printed *Charles O. Goss*; and that the said Letters Patent should be read with this correction therein that the same may conform to the record of the case in the Patent Office.

Signed and sealed this 16th day of October, A. D., 1906.

[SEAL.]

F. I. ALLEN,

Commissioner of Patents.
